[57] **CLAIM**

The ornamental design of an electric Kwanzaa lighting unit, as shown and described.

DESCRIPTION

FIG. 1 is a front elevational view of an electric Kwanzaa lighting unit embodying the present invention, with the broken line showing for illustrative purposes only and forming no part of the claimed design;

FIG. 2 is a side elevational view thereof, with the opposite side being a mirror image;

FIG. 3 is a rear elevational view of an electric Kwanzaa lighting unit;

FIG. 4 is a top plan view thereof; and,

FIG. 5 is a bottom view thereof.
